United States Patent Office

Des. 205,913

Patented Oct. 4, 1966

205,913

RECORD CARD

John E. Morse and William C. Thomas, Rochester, N.Y.,
assignors to Eastman Kodak Company, Rochester,
N.Y., a corporation of New Jersey

Filed Oct. 26, 1964, Ser. No. 82,324

Term of patent 14 years

(Cl. D59—2)

FIG. 1

FIG. 2

FIG. 3

FIG. 1 is a front elevational view of a record card showing our new design;

FIG. 2 is an edge view thereof;

FIG. 3 is a fragmentary view of another form of the notches which form, when substituted for the notches of FIG. 1, a second embodiment of our new design;

FIG. 4 is a fragmentary view of still another form of the notches which form, when substituted for the notches of FIG. 1, a third embodiment of our new design; and

FIG. 5 is a fragmentary view of still an additional form of the notches which form, when substituted for the notches of FIG. 1, a fourth embodiment of our new design.

We claim:

The ornamental design for a record card, as shown and described.
